PROCESS FOR PRODUCING GASOLINE

Filed Feb. 1, 1935

UNITED STATES PATENT OFFICE

2,097,412

PROCESS FOR PRODUCING GASOLINE

James J. Hogan, Whiting, Ind., assignor to Standard Oil Company, Chicago, Ill., a corporation of Indiana

Application February 1, 1935, Serial No. 4,509

6 Claims. (Cl. 196—48)

This invention relates to a process for the production of gasoline or other relatively light distillate from raw crude oil, or other similar relatively heavy stock containing lighter and heavier constituents.

In the treatment of raw crude oil or the like to produce gasoline, it has been a practice heretofore to distill from the crude oil by distillation a distillate stock of gas oil nature and to subject this distillate stock to cracking treatment under conditions which will convert a considerable portion thereof into hydrocarbons within the gasoline boiling range. Simultaneously during this distillation a plurality of other cuts or petroleum fractions may be separated from the original crude oil such as, for example, light naphtha or virgin gasoline, heavy naphtha, which may be reformed, kerosene and, in some cases, furnace oil. In certain instances the undistilled reduced crude from which some or all the distillate fractions above mentioned have been removed, has been subjected to a mild cracking treatment under low crack per pass conditions principally for the purpose of reducing its viscosity and to form additional quantities of gas oil. The gas oil so formed has been then subjected to more drastic cracking treatment of the nature first mentioned so as to produce a further yield of gasoline constituents.

One of the main objects of my invention is to provide a process for the treatment of hydrocarbon oil, which may be raw, crude petroleum, which will produce an improved yield of gasoline of high quality and which may be operated at a higher level of efficiency.

Another principal object of my invention is to provide a process of the character hereinbefore mentioned, for treating heavy hydrocarbon oil stock which may be of the nature of crude petroleum, wherein the individual steps of the process are carried in such relation to each other as to improve the over-all efficiency of the process.

A further salient object of my invention is to provide a process for producing gasoline and other desired end products from heavy hydrocarbon oil stock, such as crude oil, wherein the complete treatment may be carried out in simpler and more compact apparatus with a consequent reduction in original installation expense and in the continuing costs of operation.

Another and more specific object of my invention is to provide a process for treating hydrocarbon oil of the character hereinbefore mentioned wherein a heavy oil stock, which may be a topped or reduced crude, resulting from pre-

liminary distillation of raw crude, may be more effectively converted into cracking stock which can be subsequently converted into a greater yield of gasoline or other desired lower boiling hydrocarbons.

Other and more specific objects of my invention will become apparent from the more detailed description hereinafter.

The above and other objects will be attained by certain novel steps and combination of steps constituting my invention which will now be described.

In accordance with my invention a topped crude oil, or in other words a crude oil from which the lower boiling constituents have been removed, or a heavy oil stock containing a preponderance of virgin constituents, is initially subjected to viscosity breaking, or mild cracking treatment, principally for producing intermediate gas oil stock which can be subsequently subjected to more drastic cracking treatment, and the products from the initial viscosity breaking treatment are fractionated to separate low boiling constituents including light gas oil. The remainder of the products resulting from the initial viscosity breaking treatment or in other words all of the heavier constituents of the viscosity broken products boiling above the light gas oil range, such as above 650° F. or 700° F. for example, are then subjected to additional cracking or viscosity breaking treatment before final separation into end products and intermediate fractions. It should be clear from the above that, in accordance with my invention, all of the heavier constituents, of the original charging stock, boiling above light gas oil, are subjected to at least two separate and independent relatively mild cracking treatments before being separated into the final end products and intermediate fractions and that all of the light gas oil formed in the process is subjected to relatively drastic cracking conditions most suitable for production of a high yield of gasoline having high anti-knock properties.

In accordance with a more specific aspect of my invention, a topped crude or the like, substantially free of cracked products, is initially subjected to mild pyrolytic conversion, principally to form intermediate gas oil cycle stock, and the products from said conversion treatment are then introduced into an evaporator, into which other hot cracked products from the process are introduced, above an intermediate trap-out tray, which collects unvaporized constituents of the conversion products and heavy gas oil condensate sep-

arated from the said converted products and other cracked products introduced into the evaporator. The stock collected in the intermediate trap-out tray is subjected to separate cracking treatment and the cracked products from the last-named treatment are also introduced into the evaporator, but below the intermediate trap-out tray, wherein the products separate into vapors and unvaporized residue. The vapors separated are then subjected to partial fractionation to condense the heavy gas oil constituents within the evaporator, which are collected in the intermediate trap-out tray and subjected to said last-named cracking treatment. The unvaporized residue is withdrawn from the bottom of the evaporator and may be flashed to a final residuum product in accordance with the established practice.

For a better understanding of my invention reference is now made to the accompanying drawing, which is a diagrammatic view of an apparatus suitable for carrying the invention into effect.

Referring particularly to the drawing the apparatus in general may comprise a crude flash tower 1, an evaporator 2, a viscosity breaking furnace 3, a vapor phase cracking furnace 4, a soaking drum 5, a fractionator 6 together with pipe lines, pumps, gauges, receiving drums, accumulator tanks and other appurtenant equipment for carrying out the process as hereinafter described.

Fresh heavy charging stock such as crude oil, after preliminary heating to a distilling temperature, for example, by indirect heat exchange with hot products resulting from subsequent cracking steps, or after having been heated in a directly fired coil, or both, is forced through charging line 7 by pump 8 into the upper stripping section 9 of the crude flash tower 1, wherein lighter constituents thereof are separated as vapors and passed off through vapor line 10 and condenser 11 into receiving drum 12, the condensate collected in the receiving drum being, for example, light naphtha or low end point virgin gasoline. The unvaporized liquid collecting in the base of the section 9 is withdrawn through pipe 13, and passed into the intermediate portion of the second section 14 of the crude flash tower, wherein a further separation into vapors and liquids takes place. This further separation may be accomplished by additional heating or by reduction in pressure or both. The additional heating may be accomplished by passing the liquid through an indirect heat exchange 15 wherein it obtains heat from other products of the system, by passing the liquid through a separately fired coil (not shown) or it may be accomplished by direct or indirect heat exchange with a stream of highly heated vapors as will be explained more fully hereinafter.

The vapors generated travel upwardly through the section 14, and those remaining uncondensed at the top of this section pass off through vapor line 16 and condenser 17 into receiver 18, the distillate so collected being, for example, heavy naphtha which it is desired to reform. An intermediate condensate collects on trap-out tray 19, and may be forced by pump 20 through line 21 into the fractionator 6 wherein it may serve as a refluxing medium, and may at the same time be placed in a position for circulation through the vapor phase cracking furnace 4, as will be explained more fully hereinafter or it may be passed directly through line 22 to an accumulator

tank 23 which receives vapor phase cracking stock.

The unvaporized liquid is withdrawn from the bottom of the section 14 of the crude flash tower through pipe 24.

The several sections of the crude flash tower or stripper 1 are provided with bubble trays, baffles or other contacting means, as shown in the drawing, in accordance with the usual practice. The lower portion of the section 64 serves as a tar flashing chamber, as will be explained hereinafter.

Reference numerals 25, 26 and 27 indicate refluxing lines through which cool oil from an external source may be introduced for cooling and refluxing purposes in the well-known manner. Alternatively, indirect cooling coils may be placed in the tower 1, to accomplish the same purpose, or cooling may be supplied in any well-known manner.

The unvaporized liquid reduced crude withdrawn from the bottom of section 14 through conduit 24, passes to an accumulator tank 28 from which it is forced by pump 29 through the heating coil 30 located in the viscosity breaking furnace 3, from which the oil emerges, after having been subjected to mild cracking or viscosity breaking treatment principally for the purpose of producing additional quantities of light clean gas oil stock suitable for cracking in the vapor phase, and is forwarded through transfer line 31 into the upper portion of evaporator 2 above the trap-out tray 32 wherein separation of vapors from liquid residue takes place. Valve 33 is inserted in the transfer line 31 to control the relative pressures in the viscosity breaking furnace and evaporator. The vapors pass upwardly through the evaporator, undergoing partial condensation therein, this condensation being only sufficient to condense the heavier gas oil components thereof, the vapors remaining uncondensed passing off through conduit 34 and partial condenser 35, into the lower portion of the fractionator 6. Condensate formed in the partial condenser 35 may be returned through conduit 36 to the top of the evaporator 2 as a refluxing medium. The partial condenser may be omitted, if desired.

In the fractionator 6, the vapors pass upwardly and are subjected to fractionation in the well-known manner. Gasoline vapors remaining uncondensed at the top of the fractionator are withdrawn through pipe 37 and condenser 38, the condensate formed being collected in receiver 39. This condensate will be gasoline of the desired end point. It may be used by itself, or it may be combined with the light naphtha derived from the crude flashing operation and collected in the receiver 12. Either or both of these distillates may be stabilized, if desired, or be subjected to any other suitable treatment to give them the selected characteristics.

Reflux condensate collects in the base of the bubble tower 6, is removed through conduit 40, and passed to accumulator tank 23 from whence it is forced by pump 41 through line 42 into a cracking coil 43 in the vapor phase furnace 4, wherein it is raised to a cracking temperature and subjected to conversion, preferably in the vapor phase. The resulting cracked products emerge from the heating coil 43 and travel through transfer line 44 into the soaker or reaction chamber 5, wherein they undergo further conversion as a result of their contained heat, preferably under substantially the same pressure as held on the

outlet of the heating coil. The digested products emerge from the soaker through conduit 45 having pressure control valve 46, into the lower portion of the evaporator 2, wherein these products undergo separation into vapors and liquid residue. The soaker 5 may be by-passed, if desired, in which case the desired digestion may be effected within the heating coil 43 and a portion or all of the cracked products from the heating coil 43 may be passed directly through line 47, which merges with line 45 in front of reducing valve 46, into the evaporator 2.

The heavy naphtha collected in the receiver 18 is directed through the conduit 48, under pressure generated by pump 49, through the naphtha reforming coil 50 located in the vapor phase furnace 4, wherein the naphtha is raised to a high cracking temperature sufficient to cause the conversion thereof into higher anti-knock gaso-line components. The resulting reformed products are transferred from the coil 50 through the line 51, having pressure control valve 52, into the lower portion of the evaporator 2.

Heavy gas oil condensate formed in the upper portion of the evaporator 2 together with un-vaporized products from the heating coil 30, introduced into the evaporator through line 31 collects in the trap-out tray 32 located at an intermediate level in the evaporator 2, and is withdrawn therefrom through pipe 53, which leads to an accumulator tank 54, from which it is withdrawn by pipe 55 and forced by pump 56 through a heating coil 57 located in the viscosity breaking furnace 3. In this coil the oil is raised to cracking temperature and subjected to conversion into lighter products, including lighter gas oil suitable for cracking at higher temperatures in the vapor phase cracking coil 43. The resulting cracked products pass through the transfer line 40 58, having pressure control valve 59, into the lower portion of the evaporator 2, and therein undergo separation into vapors and liquids similarly to the cracked products already discussed.

A refluxing line 60 is shown for supplying cooling fluid from an external source to the evaporator 2 and another line 61 is shown for providing cooling fluid to the top of the fractionator 6, in well-known manner. Indirect cooling coils might be used for accomplishing the same purpose, in which event the cooling fluid might be the fresh charging stock, whereby the charging stock would be raised in temperature to aid in the distillation thereof. The evaporator 2 is provided with baffle plates, bubble trays, or other suitable contacting means in a well-known manner. I have indicated all of the cracked products from the several cracking and reforming coils 43, 50 and 57, as entering the evaporator 2 through separate connections. Instead all of the pipes 45, 51 and 59 might merge into a common connection leading into the evaporator. Cooling oil can be introduced into the soaker adjacent the outlet thereof and likewise into the various transfer lines, for fluxing purposes, in a well-known manner, if desired, so as to inhibit the deposition of coke. Likewise any suitable cooling arrangement may be provided for maintaining the temperature of the liquid collecting in the base of the evaporator 2 at a suitably low value to prevent deleterious coke deposition therein.

The liquid residue collecting in the base of evaporator 2 is withdrawn through conduit 62, having pressure reducing valve 63, and is introduced into the lower section 64 of the crude flash tower 1, wherein it undergoes distillation or sep-

aration into vapors and unvaporized residual stock or tar, by virtue of its contained heat, and by reduced pressure effected by means of reducing valve 63. If desired additional heat may be supplied to the liquid residue either by indirect heat exchange with hot products of the system or by means of a directly fired coil in lieu of or in conjunction with reduction in pressure.

The vapors liberated in the lower section 64 of the flash tower 1 may be withdrawn through line 10 65, provided with valve 66 and introduced into the intermediate section 14 wherein it directly contacts with fresh charging oil undergoing distillation and the heat of the vapors so introduced utilized directly in carrying out the distillation. 15

In accordance with this procedure the heavier constituents of the vapors so introduced will be condensed in the lower portion of the intermediate section 14 below the trap-out tray 19 and will be passed, along with the topped or reduced 20 crude, to the accumulator tank 28 which collects charging stock for the coil 30 and an intermediate condensate formed from the vapors so introduced will be collected with fresh oil condensate in trap-out tray 19, from whence it will pass to 25 accumulator tank 23 and/or the fractionator 6. The heavy naphtha constituents of these vapors will be withdrawn, with the heavy naphtha constituents of the original charging stock, through line 16, passing to the accumulator tank 18 which 30 supplies charging stock to the reforming coil 50.

In accordance with one phase of my invention, however, the vapors liberated from the residue in the bottom section 64 of flash tower 1 are not caused to directly contact with fresh oil undergoing distillation as before described but are withdrawn from section 64 through line 67 and after being condensed in condenser 69 may be forced by means of pump 68 to the upper portion 35 of the evaporator tower 2, above the trap-out 40 tray 32 and be subjected to fractionation in the upper end of the evaporator 2 and in the fractionator 6 along with the other cracked vapors liberated in the evaporator as before described.

If desired a portion or all of the condensate 45 from condenser 69 may pass, via line 70 and pump 71 directly to the accumulator tank 54 which supplies charging stock to the heating coil 57. A by-pass line is provided around the condenser 69 so that a portion or all of the vapors may be 50 introduced directly into the evaporator 2. If desired, a separate fractionating tower may be substituted for the condenser 69 and the vapors separately condensed and fractionated into a heavy gas oil condensate which may be passed to 55 accumulator tank 54 or to the top of the evaporator 2, a light gas oil condensate which may be passed to the top of evaporator 2 or into fractionator 6 or may be passed directly to the accumulator tank 23, and a light distillate fraction 60 which may be passed into the top of fractionator 6 or be separately collected.

The unvaporized tarry residuum from the bottom section 64 of the flash tower 1 is withdrawn from the system through line 72. 65

The various conditions, such as temperature, pressure, time of treatment, and the amount of conversion which should be effected during a single passage of the oil through the respective heating coils under which my invention may be 70 practiced to the best advantage are so inter-related and so dependent upon external factors, such as character of the original stock and the quality and specifications of the final products, that they cannot be prescribed with certainty 75

to cover all cases. From a relative point of view, the cracking conditions, such as the outlet temperature, for the heating coils 30, 57, 43 and 50 should be increasingly drastic in the order mentioned. Conversion per pass and rate of heat input will be usually in the order of coils 57, 30, 43 and 50.

As an aid in carrying out the invention to the best advantage the following examples of 10 temperatures, pressures, conversion per pass and other conditions are given. It will be understood, however, that these examples are intended merely for general guidance and are not inserted for the purpose of limiting the invention to the 15 particular values given.

For example, when treating common crude oils, such as Mid-Continent crude or crudes of similar composition, to produce gasoline meeting standard specification, such as gasoline having 20 an endpoint of about 400° F. and having an octane value of about 70 C. F. R.—M. (Cooperative Fuel Research—Motor Method) the temperature at the outlet of the vis-breaking coil 30 may be of the order of the 800–850° F., the outlet 25 temperature of the coil 57 may be of the order of 850–925° F., the outlet of heating coil 43 may range from 900–1000° F. and the outlet temperature of the coil 50 may be of the order of 1000–1100° F.

30 As a specific example, when processing Mid-Continent crude having a gravity of about 37° A. P. I. to produce 400° F. end point gasoline having an octane value of approximately 70 (C. F. R.—M.) the outlet temperature of the heating coil 35 30 may approximate 850° F., that of the heating coil 57 may approximate 900° F., that of the heating coil 43 may approximate 975° F. and the outlet temperature of the reforming coil 50 may approximate 1050° F.

40 The temperature of the soaking drum 5 may be maintained slightly below the outlet temperature of the heating coil 43. The temperature at the bottom of evaporator 2 should be maintained sufficiently low to prevent substantial coke deposition 45 and may be in the neighborhood of about 800° F. The temperature at the top of the evaporator should be controlled so as to condense heavy gas oil constituents of the vapors within the upper region of the evaporator. For example, the top 50 temperature of the evaporator may be controlled to condense constituents boiling above 650–700° F. The top temperature of the fractionator may be controlled to produce gasoline of desired end point.

55 The fresh oil before being introduced into the upper section 9 of the flash tower 1 may be pre-heated to a temperature in the neighborhood of 300–400° F. and may be subsequently heated, either by direct contact with vapor products from 60 the bottom section 64 of flash tower 1, and/or by additional heating to a temperature approximating 650–700° F.

65 The pressures maintained in various parts of the equipment is largely a matter of individual preference depending to some extent on the quality of end products desired. The whole equipment may be under substantially uniform pressure except for the necessary differential to cause the flow of products as hereinbefore described 70 and may range from atmospheric to several hundred pounds per square inch. In certain respects, particularly in the distillation and vaporization equipment, pressure is reciprocal to temperature in that by reducing pressure the same effect may 75 be obtained as by increasing the temperature and

consequently by maintaining the products issuing from the heating coils under substantial pressure, successive reductions in pressure may be used in carrying out subsequent distillation and vaporization. Furthermore, by maintaining the heating coils in which cracking takes place under substantial pressure, the amount of fixed gases formed during the cracking may be reduced.

As a guide in carrying out my invention to better advantage, the pressure in the evaporator 2 10 may be maintained, for example in the neighborhood of 200 pounds per square inch and the pressure in the fractionator 6 slightly lower.

The outlet pressure on all of the heating coils 15 may be substantially the same, and may be slightly in excess of the pressure maintained in the evaporator or may be considerably in excess thereof so that reduction in pressure, by means of reducing valves in the transfer lines may be utilized to aid in carrying out the vaporization. Also the 20 lower section 64 into which the cracked residue from the bottom of the evaporator 2 is introduced is preferably maintained at a pressure materially below the pressure in the evaporator by means of reducing valve 63 in line 62 so that the 25 cracked residue can be distilled by its contained heat.

30 In order to avoid excessive gas loss and improve the anti-knock properties of the reformed gasoline it is ordinarily deemed desirable to maintain the oil passing through the reforming coil 50 under a relatively high pressure, such as an outlet pressure of from about 500 to about 700 pounds per square inch. The outlet pressure of any one or more of the remaining coils may vary from 35 slightly in excess of evaporator pressure to relatively high pressure such as from 500 to 700 pounds per square inch.

35 The extent of conversion, during a single passage of the charging oils through the respective 40 cracking and viscosity breaking coils into gasoline constituents, or in other words the amount of conversion per pass, may be used to control the cracking and viscosity breaking conditions in the 45 respective coils.

As a guide for controlling the cracking conditions, such as temperature, time of treatment, and rate of heat input, the following examples are given.

50 For example, the conditions within the viscosity breaking coil 30 may be controlled so as to convert from 10% to 20% of the original reduced crude charge into gasoline constituents preferably in the neighborhood of 15%. In this connection it will be understood that the amount of gasoline formed during passage of the oil through this coil is of secondary importance since the principal purpose of this treatment is to produce suitable stock for the vapor phase coil 43 wherein the oil is subjected to more suitable conditions for the production of gasoline. The amount of gasoline formed during passage of the oil through coil 30 does, however, in a measure, indicate the amount of conversion of the oil into gas oil cracking stock. In cases where vapors from the tar flashing drum, forming the bottom section 64 of flash tower 1 are not commingled with crude being distilled in the intermediate section 14 the amount of conversion in coil 30 may be somewhat 60 increased without introducing coking troubles. 65

70 The coil 57 may be controlled so as to convert from 6% to 15%, preferably about 10% of the charging stock into gasoline constituents and coil 43 may be controlled to effect from about 15% to 75

25%, or more, of the charging stock into gasoline, preferably about 20%.

By carrying out the process as hereinbefore described, it is possible to effect the desired conversion of the several components of the original fresh oil under the optimum conditions. The inclusion of the trap-out tray 32 and the associated heating coil 57 assures that the heavy gas oil condensate, and unvaporized products from the 10 cracking coil 30, which are not suitable for cracking in the vapor phase furnace on account of coke forming tendencies, can be separately converted under the conditions best adapted to cause a maximum conversion thereof. The 15 provision of the cracking coil 57 also lightens the load on the viscosity breaking furnace 30 and not only permits greater throughput of reduced crude in that furnace, but also limits the stock going through that furnace either strictly to 20 virgin components or to a greater proportion of virgin components and to components which are more nearly of like characteristics. The viscosity breaking furnace 30 can, therefore, be operated under the best conditions for cracking the heavy 25 reduced crude, while the heavy cracked condensate and unvaporized products from coil 30 which are collected on trap-out tray 32 may be separately converted under conditions best suited to their characteristics, the clean gas oil cracking 30 stock from the base of the fractionator and the heavy naphtha from the crude flash tower being separately treated in individual furnace coils, to cause the desired conversion thereof, under conditions properly selected for the stocks in question 35 without consideration for other of the fractions.

If desired the cracked products from the viscosity breaking coil 30 may be introduced into a separate evaporator, (not shown), and the bottoms from the separate evaporator combined with condensate from the trap-out tray 32 for treatment in coil 57. The vapors from the added evaporator may be separately fractionated in order to form gasoline distillate and light clean 45 gas oil condensate suitable for vapor phase cracking, and the gasoline distillate so segregated can then be combined, either with or without previous reformation, with the cracked gasoline collected in receiver 39 and/or the virgin light 50 naphtha collected in receiver 12, to form a desired blended product. The heavy gas oil condensate corresponding to gas oil condensed above the trap-out tray 32, may be retained with the bottoms in the added evaporator and be combined with condensate from the tray 32 of evaporator 2 for treatment in coil 57.

While I have described my invention in connection with a specific apparatus illustrated diagrammatically in the drawing, it is to be understood that the invention may be carried out in various other types of apparatus. For example, while I have shown two separate furnaces with two coils in each furnace it will be clear that all of the coils might, if desired, be mounted in a 65 single furnace or that each coil might be mounted in a separate furnace. It will also be clear that the position of the coils in the furnace and the routing of the oil through the respective coils will be in accordance with established practices 70 in this respect. Also, if desired, additional soaking drums may be provided for each of the coils 30 and 57.

It will be understood that various valves, such as shown on the drawing but not referred to by 75 reference characters, and possibly others not

shown, may be used for control purposes. Auxiliary heat exchangers, cooling coils, pressure, flow and temperature controllers and other appurtenant apparatus have been omitted from the drawing in the interest of simplicity, but should be provided in accordance with best established practice. 5

While the preferred embodiment has been described for illustrative purposes, it should be understood that my invention embraces such 10 other modifications and variations as come within the spirit and scope thereof and that it is not my intention to limit the invention except as necessary to distinguish from prior art.

In the appended claims I have attempted to 15 define the invention in all its various forms and it should be understood that it is not my intention to dedicate or abandon any novel features thereof.

I claim:

1. In a process for converting raw crude oil into lower boiling hydrocarbons suitable for motor fuel wherein the original raw crude is initially distilled to separate therefrom a light virgin naphtha, a heavy virgin naphtha which is subsequently subjected to a reforming treatment for the purpose of improving its anti-knock properties thereof, a light gas oil fraction which is subjected to cracking treatment to convert the same into motor fuel constituents, and a topped or reduced crude, and wherein the products from the reforming treatment and from said cracking treatment are separated into vapors and residual products in a common zone, the vapor fractionated to separate a heavy gas oil condensate, a light 30 gas oil condensate, and a desired distillate product; the improvement which comprises subjecting said topped crude to viscosity breaking treatment, removing lower boiling constituents including a light gas oil from the remainder of said 35 products resulting from the viscosity breaking treatment, combining heavy gas oil resulting from the first-mentioned cracking treatment with said remainder, subjecting said composite mixture to separate and independent cracking treatment, and separating a desired distillate product from the products resulting from said last-mentioned cracking treatment. 40

2. A method of producing motor fuel from raw crude oil which comprises initially distilling said raw crude oil to vaporize lower boiling constituents therefrom, separating a light gas oil condensate from the vapors so separated, heating the unvaporized reduced crude to a viscosity breaking temperature while passing in a confined stream through a heating coil, thereafter introducing the products into an enlarged zone wherein vapors and liquid products separate, fractionating said vapors, separately collecting light gas oil condensate and a desired distillate product, withdrawing 50 unvaporized constituents and heavy gas oil condensate from said enlarged zone, heating said withdrawn products to a cracking temperature while passing in a confined stream through a heating coil, thereafter introducing the products 55 from said last-named heating coil into said enlarged zone below the point of withdrawal of said unvaporized constituents and heavy gas oil condensate wherein vapors and liquid products thereof separate, fractionating said last-named 60 vapors with said second-mentioned vapors, in a common fractionating zone, combining light gas oil resulting from the initial distillation of the raw crude with light gas oil condensate resulting 65 from said viscosity breaking and cracking treatment. 70

ment, heating the combined light gas oil condensate stock to a relatively high cracking temperature compared to said last-mentioned cracking temperature while passing in a confined stream 5 through a heating coil, thereafter introducing the products from said last-named heating coil into said enlarged zone below the point of withdrawal of unvaporized constituents and heavy gas oil condensate wherein vapors and liquid products 10 thereof separate, withdrawing unvaporized residue from the bottom of said enlarged zone, distilling the unvaporized residue withdrawn from said enlarged zone and introducing distillate products from said last-named distillation into said enlarged zone.

3. A method of producing motor fuel from raw crude oil which comprises initially distilling said raw crude oil to vaporize lower boiling constituents therefrom, separating a light gas oil condensate from the vapors so separated, heating the unvaporized reduced crude to a viscosity breaking temperature while passing in a confined stream through a heating coil, thereafter introducing the products into an enlarged zone where- 20 in vapors and liquid products separate, fractionating said vapors, separately collecting light gas oil condensate and a desired distillate product, withdrawing unvaporized constituents and heavy gas oil condensate from said enlarged zone, heat- 25 ing said withdrawn products to a cracking temperature while passing in a confined stream through a heating coil, thereafter introducing the products from said last-named heating coil into said enlarged zone below the point of withdrawal 30 of said unvaporized constituents and heavy gas oil condensate wherein vapors and liquid products thereof separate, fractionating said last-named vapors with said second-mentioned vapors, in a common fractionating zone, combining light gas oil resulting from the initial distillation of the raw crude with light gas oil condensate result- 35 ing from said viscosity breaking and cracking treatment, heating the combined light gas oil condensate stock to a relatively high cracking tem- 40 perature compared to said last-mentioned crack- 45 ing temperature while passing in a confined stream through a heating coil, thereafter introducing the products from said last-named heating coil into said enlarged zone below the point of withdrawal of unvaporized constituents and heavy gas oil condensate wherein vapors and liquid products thereof separate, withdrawing un- 50 vaporized residue from the bottom of said enlarged zone, distilling the unvaporized residue withdrawn from said enlarged zone and utilizing heat of vapors resulting from said last-named cracking treatment in the initial distillation of said raw crude oil.

4. A method of producing motor fuel from raw crude oil which comprises initially distilling said raw crude oil to vaporize lower boiling constituents therefrom, separating a light gas oil condensate from the vapors so separated, heating the unvaporized reduced crude to a viscosity breaking temperature while passing in a confined stream through a heating coil, thereafter introducing the products into an enlarged zone wherein vapors and liquid products separate, fractionating said vapors, separately collecting light gas oil condensate and a desired distillate product, withdraw- 60 ing unvaporized constituents and heavy gas oil condensate from said enlarged zone, heating said withdrawn products to a cracking temperature while passing in a confined stream through a heating coil, thereafter introducing the products 65

from said last-named heating coil into said enlarged zone below the point of withdrawal of said unvaporized constituents and heavy gas oil condensate wherein vapors and liquid products thereof separate, fractionating said last-named vapors with said second-mentioned vapors, in a common fractionating zone, combining light gas oil resulting from the initial distillation of the raw crude with light gas oil condensate resulting from said viscosity breaking and cracking treatment, heating the combined light gas oil condensate stock to a relatively high cracking temperature compared to said last-mentioned cracking temperature while passing in a confined stream through a heating coil, thereafter introducing the products from said last-named heating coil into said enlarged zone below the point of withdrawal of unvaporized constituents and heavy gas oil condensate wherein vapors and liquid products thereof separate, withdrawing unvaporized residue from the bottom of said enlarged zone, further distilling unvaporized residue withdrawn from said enlarged zone, combining a distillate product resulting from said last-named distillation with products passing to said second-named heating coil.

5. The method of producing motor fuel which comprises heating reduced crude to a viscosity breaking temperature while passing in a confined stream through a heating coil and thereafter separating the cracked products into vapors and liquids in an enlarged zone, withdrawing unvaporized constituents and heavy gas oil condensate from said enlarged zone, heating the withdrawn products to a cracking temperature while passing in a confined stream through a second heating coil, thereafter introducing the cracked products from said last-named heating coil into said enlarged zone below the point of withdrawal of said unvaporized constituents and heavy gas oil condensate to cause separation of the said cracked products last-mentioned into vapors and liquids, fractionating said last-named vapors with said first-mentioned vapors in a common fractionating zone to form a reflux condensate and a desired distillate product, heating reflux condensate so obtained to a relatively high cracking temperature compared to said last-mentioned cracking temperature while passing in a confined stream through a third heating coil, introducing the resulting cracked products from said last-named heating coil into said enlarged zone below the point of withdrawal of unvaporized constituents and heavy gas oil condensate, withdrawing unvaporized residue from the bottom of said enlarged zone, flashing unvaporized residue withdrawn from the bottom of said enlarged zone in a zone of reduced pressure and combining heavier constituents of the flashed vapors with the reduced crude which is passed to the first-men- 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 5 densate to cause separation of the said cracked products last-mentioned into vapors and liquids, fractionating said last-named vapors with said first-mentioned vapors in a common fractionating zone to form a reflux condensate and a desired distillate product, heating reflux condensate so obtained to a relatively high cracking temperature compared to said last-mentioned cracking temperature while passing in a confined stream through a third heating coil, introducing the resulting cracked products from said last-named heating coil into said enlarged zone below the

point of withdrawal of unvaporized constituents and heavy gas oil condensate, withdrawing unvaporized residue from the bottom of said enlarged zone, subjecting unvaporized residue from the bottom of said enlarged zone to a flashing 5 operation in a zone of reduced pressure, combining heavier constituents of the flashed vapors with the reduced crude passed to the said heating coil first-mentioned and combining lighter constituents thereof with the reflux condensate 10 passed to said heating coil third-mentioned.

JAMES J. HOGAN.
